HOSIERY PRESS

Edward J. Schremp, Flushing, N. Y., assignor,
by mesne assignments, to The Prosperity Com-
pany, Inc., a corporation of New York

Application February 21, 1924, Serial No. 694,210
Renewed November 25, 1931

42 Claims. (Cl. 223—17)

This invention relates to improved textile or fabric garment finishing methods and machines therefor, and more particularly relates to garment driers, pressers and printers for finishing apparel.

An object of the invention is to provide an improved method of preparing and finishing garments and to provide new instrumentalities for performing the same in a machine for pressing, 10 drying and printing garments; and for the purposes of the present disclosure I have shown a machine particularly adapted for hosiery work whereby the hose is finished by the improved method which increases the production with a 15 consequent reduction in cost. The garments are dried and may be pressed as well and are then printed with the manufacturer's trade mark, size number, the name thereof, or such other data as it is desired to apply to the hosiery or other 20 garments.

An additional object and feature of the invention is to provide a machine which performs the usual three operations in finishing hosiery namely, drying, pressing, and printing. It has been 25 the practice to perform these essential operations by separate machines, but my invention enables the hosiery manufacturer to coordinate all the work and carry it out on one and the same machine and at the same press setting which is 30 to say that the three operations are executed while the hosiery or other work is in the press and without removing the work until the goods are dried, pressed and printed.

A still further object is to utilize the features 35 of the hosiery tray invention as disclosed in my former application Serial Number 625,428 filed in the United States Patent Office March 15, 1923 and make improvements thereon.

A further object of the invention is to produce 40 a pressing machine having improved facilities for steam and air spraying garments whereby they may be subjected to a steam dampening operation and immediately followed by a hot and cold air treatment for the purpose of quickly drying and cooling the garment without permitting condensate to collect on the garment which is to say that the work may be steam treated and the steam removed before it has had time to condense and consequently the work of finishing the 45 garments at one press setting is very rapidly carried out inasmuch as the work, in such cases as received at the machine dry, is not permitted to be made wet thus saving the time heretofore required to dry garments when cold air was used. 50 In my improvements, hot air first carries away

the steam thus leaving a dry but hot garment; and then a blast of cold air carries away the heat.

While I do not attempt to enumerate each and every object of the invention, I will say that another object is to enable a modern type garment or clothes press to be converted into a hosiery press which by the way tends toward economy for the reason that manufacturing facilities are more largely standardized due to less 60 number of models or types of presses under construction or carried on hand with a consequently larger commercial use because the price is brought down to a point where it is in range with an increased number of users.

The accompanying drawings illustrate one preferred form of the invention, and it is understood how changes in construction and mode of operation may be carried out without departing from the scope of my invention.

Figure 1 illustrates a plan view of my improved press designed for hosiery, gloves, other knit goods and the like.

Figures 2 and 3 illustrate respectively sectional views as developed upon section lines 2—2 and 80 3—3 of Figure 1, (Figure 3 also being developed on the line 3—3 of Figure 8) the first detail showing a spring pressed clip to tautly hold hosiery on the form, and the second detail showing a ratchet and detent device for positively holding 85 a garment form unit in one of two positions.

Figure 4 shows a front elevation of the pressing machine and here the table is omitted for clearness, the said table being shown in Figures 1 and 7.

Figure 5 shows a detailed fragmentary end view of the machine jaws closed with a printing mechanism adapted to move in and out of the press whereby the press head may first close to perform the spraying, drying and pressing operations, and thereafter the printing mechanism functions.

Figure 6 illustrates an enlarged side fragmentary view of the pressing machine with one of the pressing members thereof shown in section for the purpose of illustrating my improved structure as well as serving to explain the improvements in methods employed for treating garments.

Figure 7 illustrates a side elevation of the machine with open jaws and garment form unit outstanding from the press and over the work table.

Figure 8 shows a simplified garment former unit serving to facilitate the pressing and print-

ing and finishing of garments and particularly hosiery and which may be manufactured and sold separately as an attachment.

As already mentioned, I may construct this garment finisher and printer by utilizing a conventional steam garment press and accordingly reference is now made to the drawings for a more detailed description of the invention where a pressing machine, upon which the improvements are constructed and installed, is illustrated; and a pressing machine frame 10 pivotally supports a press lever 11 on the forward end of which is mounted a head 12 which cooperates or opens and closes upon a buck 13. The pressing members 12 and 13 open and close in the nature of jaws and the work is placed thereinbetween for steaming, heating, drying and pressing as well as for the printing thereof. The rear end of the press lever 11 carries a link 14 pivoted thereto which pivotally connects with the upper end of a link 15 integral with a manual press jaw operating means as a pedal 16. The links 14 and 15 constitute a main operating toggle which straightens by thrusting down the pedal 16 thereby closing the jaw or pressing members 12 and 13. This type of pressing machine may be equipped with steam spraying, heating and air treatment facilities as to either pressing member or both depending somewhat on the character of work for which the machine is designed; and the drawings show a piping system connecting with the lower pressing jaw member, the buck, for the purposes mentioned and to be hereinafter described.

The pressing jaws 12 and 13 possess a substantially large spread to enable a plurality of garments to be stretched out therein between which is to say that the said pressing members are preferably rectangular in shape with a large area and have a long reach. This essentially means that the pressing head is of great weight and the instrumentalities for raising and lowering it constitute an important factor to be reckoned with especially where the press is manually operated and manual operation is more desirable for the sake of the operator's safety as well as for economy. Having these points in view I so construct the operating toggle 14-15 that the pedal 16 itself undergoes a greater travel than the lift of the head jaw 12 and in this way the press opens a very short distance only wide enough to admit the garment former unit. Thus the pedal 16 possesses a leverage over the head and the head is closed with little manual effort.

Referring now more particularly to Figure 6 of the drawings, the said buck 13 is preferably made with a foraminous or perforated press face 18 provided with a steam and air spray chamber 19 directly underneath the foraminous face. The buck is partitioned with walls 20 and 21 which provide a fluid heating chamber 22 preferably located midway of the buck 13 for the purpose of uniformly distributing the heat throughout this pressing member. An air heating chamber 23 is formed in the buck and preferably provided with a plurality of radiating ribs 24 affording a large radiating surface by which air is heated as it is blown therethrough. The combination air and steam spraying chamber 19 is directly connected by a passage to the hot air chamber 23 and receives hot air under pressure to spray out through the perforated press plate as later described. The spray chamber is also connected to the fluid heating chamber 22 by a valve 26 which is normally closed to prevent steam from

spraying into the chamber 19. The valve 26 is connected to a handle 27 whereby the operator may open the valve 26 to discharge steam from the heating chamber 22 upwardly into the steam chamber 19; and steam ejects from the steam chamber upwardly through the perforated face onto the work thereby steam moistening and heating the work and conditioning it for pressing as well as raising the nap by steam expansion. The steam spray treatment of garments is carried out for various purposes, for in the finishing of garments that come to the press dry, it is usually desirable to steam moisten them to render the garment more susceptible to the pressing and finishing operations, and it is understood, after the steam dampening and heating operation is effected, that it then becomes desirable to quickly dry the garment whereby it is made ready for packing in boxes or cases immediately the garment is finished as well as being made ready for immediate use.

While the steam and air treatment of garments is not in itself new, I hereinafter describe my improved combined means employed for quickly drying and cooling the garment following the heating operation. An air pump 30 delivers air through a pipe 31 to the air heating chamber 23 and forces the air upwardly through the spray chamber 19 out through the work, and the air becomes heated as it passes through the chamber 23 and thus the heated air serves to drive the steam previously injected therewith, from the work. Hot air more expeditiously drives the moisture from the work than cold air; and so it follows that I have shown means for heating air and blowing it through the work following the steam treatment thereof.

Having described above how the work is steam treated, and then treated by the hot air drying operation, it is now understood why it is desired to thereafter blow or draw cold air through the garment for it is appreciated how the cold air quickly removes the heat from the garment once the moisture is carried away by hot air. To this end a pipe 32 connects with the pump 30 and with a passage 33 in the buck leading to the foraminous chamber 19. A valve 34 is mounted in the pipe 32 and a valve 35 is mounted in the pipe 31. A valve operating handle 36 connects with both of the valves 34 and 35 in such a way that one valve is always open while the other valve is always closed. The valve 35 is made with an exhaust port 37 which leads to atmosphere thereby enabling the pipe 31 to be vented when the valve 35 is closed. The pump 30 draws cold air downwardly through the foraminous face of the chamber 19 and through the pipe 32 and discharges it out through the exhaust port 37 when the valve 34 is open, and during which time the valve 35 is closed with the exhaust port 37 open. The suction pump 30 displaces a large volume of air downwardly through the face of the buck 13 and discharges this air out through the port 37 for the purpose of cooling the work or the garments held in between the pressing jaws 12 and 13. When however, the operator swings the handle 36 to change the relative position of the valves 34 and 35 it follows that the valve 35 is opened, the exhaust port 37 is closed, and the valve 34 closed, whereupon the air is drawn into the pump at its ordinary intake and blows through the heating chamber 23 upwardly through the foraminous buck to produce a hot air draught through the work which is always desirable for a short period just prior to drawing

cold air therethrough for the reason that the preliminary forcing of warm air through the work removes the steam dampness from the garment thereby enabling the cold air to quickly cool the garment.

In treating garments such as suits, knit goods, gloves, hosiery and the like on a pressing machine as hereinbefore described, the garment is inserted between the pressing members whereupon steam is ejected through the garment either from the head 12 or from the buck 13 in case the garment is brought dry to the pressing machine. The steam softens the fabric, raises the nap, and conditions it for pressing. Furthermore jaw pressure is applied through the pedal mechanism 16, or in some cases where high pressure is desired the pressure is applied through power means, for the purpose of laying down and flattening thick seams and the like. In order to quickly dry and cool steam pressed garments, it follows that the steam must be removed and rather than produce a blast of cold air through the garment which would condense the steam and make the garment wet, I preferably induce a strong current of warm air upwardly through the garment, as hereinbefore explained, which more quickly removes the moisture than cold air for it is understood how the hot air will remove the vaporized steam and moisture from the garment without tending to condense it therein. Subsequently a short blast of cold air is projected downwardly through the garment for the purpose of removing the heat as imparted thereto by the hot air blast previously passed through the garment. The garment is then very dry and quite cool and when removed from the buck will hold its shape more readily than when treated by methods now in use.

A description will now be given of the hosiery pressing equipment used in conjunction with the pressing machine as already described, and for the purpose of this disclosure a hosiery pressing form or tray, or garment form unit, is illustrated in the drawings and this accessory device may be manufactured and sold separately from the pressing machine, as apparent from Figure 8, whereby pressing machines in present-day use may be equipped to press, finish, and print manufacturer's data on hosiery, gloves, or other knit goods of the kind usually stretched and dried or treated on forms. The hosiery trays or garment form units for other apparel are preferably made in pairs and mounted on the pressing machine for independent operation whereby one tray unit is being pressed, dried and printed, while the other form is being loaded or filled by the operator.

A standard or bracket arm 40 is anchored to the pressing machine frame and stands outwardly from the buck and head and is provided with a vertical bearing 41. A hub 42 has a journal pin 43 fixed thereto and this pin is pivotally disposed in the bearing 41. The pin 43 preferably rests on a frictionless point such as a ball 44 and a screw 45 supports the ball in position to hold the axis of the hub 42 in alignment with the meeting plane of the pressing members 12 and 13. The screw 45 may be adjusted up and down to move the hub 42 so that the form unit or tray carried thereby is brought into exact alignment and into the plane of the foraminous pressing face 18 of the buck 13.

A tray or form carrying shaft arm 47 is pivotally mounted in the hub 42 and is fitted with a collar 48 which is made with a ratchet de-

tent which ratchets over and snaps into a spring pressed plunger 49 thus serving to hold the outstanding shaft arm 47 in proper position as related with the pressing head and buck. The operation of moving the tray 47 into the press is facilitated by the ratchet and detent 49 inasmuch as the said plunger 49 aids the operator in bringing the tray 47 to rest at a predetermined point, and this is important for the reason that the garments must be moved in and out of the press and brought to rest at substantially the same point each time in order that the printing machine, to be described, bear down uniformly upon the toe of the stocking or upon such other point on each garment as may be desired. A similar spring pressed plunger 50 is carried in a lug 51 formed integral and standing forwardly of the journal pin 43, and the lock collar 48 snaps into registry with the locking means 50 and holds the tray 47 in outstanding position when the said tray is swung outwardly from the pressing machine.

A plurality of garment or work-carrying forms 53 are shown in this instance to be hosiery forms and the said forms may be stamped from solid sheet metal or may be made of wire. Both such structures are shown in the plan view Figure 1, and either are suitable for use. The forms 53 are rigidly anchored to the rod 47 and taken together as a unit constitute a tray or garment form unit which is quite light in construction and capable of being rapidly moved in and out of the pressing machine. The outer free end of the shaft arm 47 carries a handle 54 anchored thereto, and the operator may swing the hosiery tray into a vertical position by twisting the handle, and in this connection the collar 48 has ratchet catches 46 which snap into the lock plungers 49 and 50 to hold the form unit in desired horizontal or vertical position. Figure 115 shows one tray unit as removed from the pressing machine and swung into a vertical position thereby enabling the operator to more readily fill the forms 53 by slipping the hosiery or other garments down thereupon.

The hosiery tray 47 swings very easily upon the pivot bearings 43, and it is to be appreciated that while one form is in the press undergoing a heating and drying treatment, that the operator may readily turn to the other outstanding tray 125 and fill it with garments whereupon the first garments undergoing press treatment have by that time become dried and are ready for printing and removal from the press. The two pressing trays stand outwardly in front of the pressing machine requiring substantially the same space as the length of the pressing machine. The operator is afforded sufficient working room between the two outstanding trays, and is not therefore put to the necessity of walking around the press or to either side thereof, for he may uniformly work from the front of the machine all the time both in loading the trays and inserting and removing them from the press.

A substantially large work table embraces the 140 entire machine and is so designed that the surface thereof spreads out underneath the operating jaw parts and garment former units. To this end a table 70 is disposed underneath the jaws, and spaced parallel tables 71 stand outwardly at the front of the machine and underneath the outstanding garment form units. Thus a substantially large size U-shaped table is provided with the operating pedal 16 placed therein between which enables the operator to 150

conveniently work all parts from the front of the machine. The tables receive and hold the work as it comes to and from the machine. The outstanding table parts 71 are supported on a reach bar 72 which is in turn anchored to an arm 73 made a part of the standard 40. The table projections 71 together with the standard 40 and arm 73 may be constructed separately from pressing machines and sold as attachments as well as the swinging garment form unit 47. Or the tray unit Figure 8 may be used to great advantage where it is not desirable to pivotally mount the swinging unit on the machine.

As shown in Figures 1, 3 and 8, a spring pressure clip or clamp 52 is carried by the shaft arm and cooperates with each garment form 53 to grasp and hold the garment in taut and stretched condition over the form during the hosiery finishing operation. The operator depresses the outer end of the clips to insert and release the hose.

A description will now be given of the printing device used in conjunction with the pressing and drying machine. Printing material in the nature of transfer tape 56 carries the manufacturer's data such as his trade mark, label, size of the garment the brand and quality thereof; and it is desirable to imprint this data from the transfer tape 56 onto the garment or hosiery 57. The printing operation is more expeditiously effected by application thereof to the dried garment, and it is appreciated that the press jaws should be first closed for the purpose of drying out the wet dyed hosiery when working on goods and apparel of that nature. I have therefore devised a printing mechanism which moves the printing tape material 56 out of the pressing machine for the first closing stroke of the press head thereby enabling the garment to be dried. The head is then lifted for the purpose of inserting the printed material and closed thru a short quick stroke to transfer by heat and pressure the manufacturer's data from the transfer tape 56 onto the garment 57.

To the above ends, brackets 58 stand outwardly from the rear of the head and they are made with slots 59 in which a reel carrying arm 60 is slidably retained. The reel carrying arm 60 is bent forwardly on each end thereof and journals a reel 61. The reels 61 are held in spaced alignment with the pressing members and the transfer tape 56 is rolled off of one reel onto the other. One reel is preferably fitted with a crank 62 projecting forwardly in of reach of the operator. Each reel is equipped with spring clip retainers 63 which enables the reels to be removed for the purpose of drawing away the old and used tape and for replacing the new roll thereon. A handle 64 is employed for operating the printing device and projects forward across the head and is mounted in slide bearings 65. The operator grasps the handle 64 and thrusts rearwardly to move the reels and printing material outwardly from under the press head, and similarly he pulls forwardly on the handle to bring the transfer tape 56 directly over the toe of the hosiery 57. Figures 1 and 5 show the printing tape reels in operative printing position while Figure 6 shows the said reels thrust rearwardly and out of the alignment with the pressing jaws.

In the general operation of the pressing machine as devoted to hosiery finishing work, it is appreciated how the operator loads or fills the forms 53 with hosiery 57 and swings one of the

tray units into pressing position whereupon the operator thrusts the printing control handle 64 rearwardly and closes the head 12 down upon the work to heat treat and dry the same. The operator then returns to filling the outstanding garment tray, and by the time it is filled, he returns to the pressing machine and causes the head to be lifted whereupon he pulls the printing control handle 64 forwardly to slip the transfer tape 56 over the hosiery toes. A quick and short stroke or application of the head imprints the garments whereupon the operator permits the jaw head 12 to again open. The operator now turns the crank 62 until the used tape has been wound upon the crank reel whereupon the operation of pressing and printing the next form unit is carried out.

Referring again to Figure 8 it is noted I have constructed a garment form handling unit consisting of a shaft arm 75 carrying a plurality of hosiery forms 76 with handles 77 by which the device is picked up and inserted in a drying machine or press; and clamps 78 may be mounted upon each individual form to grasp and hold the work.

What I claim is:

1. That improvement in the method of treating garments by successively applying pressure which consists in inserting a damp garment in a hot press, and closing the press to dry the garment, opening the press and inserting printing material on the dry garment, and again closing the press to perform the printing operation upon the dry garment.

2. That improvement in the method of finishing wearing apparel by pressing and stamping it at one setting, which includes spreading or stretching the garment upon a form, inserting the form and garment into the press, closing the press to heat the garment and opening the press to expose the dry garment, inserting transfer printing tape in the press across the garment at the point where the manufacturer's data is to be shown, and again closing the press to transfer the data from the tape to the garment.

3. That improvement in the method of finishing garments which consists in subjecting the garment to heat and pressure, followed by subjecting the heated and pressed garment to an air draught, disposing printing tape material across the garment, and again applying heat and pressure to perform the printing operation upon the garment.

4. That improvement in the method of finishing garments which consists in subjecting the garment to heat and pressure, followed by subjecting the heated and pressed garment to an air draught, disposing printing tape material across the garment, again applying heat and pressure to perform the printing operation upon the garment, and finally subjecting the garment to a cold air draught to cool the printed and pressed garment.

5. That improvement in the method of finishing garments or the like which consists in subjecting the garment to a moistening and heating treatment, directing a blast of warm air through the garment to remove the moisture therefrom, and directing a blast of cold air through the garment to remove the heat therefrom.

6. That improvement in the method of finishing garments and the like which consists in mounting or stretching the garments over forms, inserting the forms in a press, drying and pressing the garments therein, disposing a strip of

printing material uniformly across the garments at the place thereon where the printed data is desired, and subjecting the garments and printing material to heat and pressure to perform the printing operation.

5 7. That improvement in the method of finishing garments or the like which consists in subjecting the garment to a heating and dampening treatment, directing a blast of warm air through the garment to remove the moisture therefrom, directing a blast of cold air through the garment to remove the heat therefrom, disposing printing tape across the garment, and finally subjecting the garment and tape to heat and pressure to perform the printing operation.

10 8. That improvement in the method of finishing garments or the like which consists in subjecting the garment to a heating and dampening treatment, directing a blast of warm air through the garment to remove the moisture therefrom, directing a blast of cold air through the garment to remove the heat therefrom, subjecting the said garment to pressure during the successive treatments, removing the pressure and inserting trans-

25 fer printing tape, and again applying pressure to perform the printing operation on the garment.

9. A machine comprising in combination, pressing members movable one in relation to the other, means for performing an opening and closing 30 movement of the press, printing means related with the machine, means for moving the printing means into the press during one closing movement and to remove the printing means from the press during the next closing movement, means for 35 heating the press, and steam spraying means to dampen the work.

10 10. A machine comprising in combination, pressing members movable one in relation to the other, means for performing an opening and closing 40 movement of the press, printing means related with the machine, means for moving the printing means into the press during one closing movement and to remove the printing means from the press during the next closing movement, means for 45 heating the press, steam spraying means to dampen the work, and a suction means for drying the work.

11. A machine comprising in combination, jaw 50 members into which the work is inserted, means for operating the jaws, printing mechanism related with the jaw members and supporting printing material, operating means forming part of the mechanism by which the printing material is advanced through the jaw members, means 55 related with the jaw members to steam spray the work to be printed, means for heating the jaws, means for blowing hot air over the work, and means for drawing cold air through the work.

12. A machine comprising cooperating press- 60 ing members movable one in relation to the other into which the work is inserted, operating means for opening and closing the members, means provided to heat the pressing members, an air chamber provided in a member in which air is heated, a 65 foraminous spray chamber carried by a pressing member and having connection with the heating chamber, means for driving the heated air from the heating chamber up through the foraminous spray chamber onto the work, and suction means connected with the spray chamber for drawing cold air down through the chamber and out of the machine.

70 13. A machine comprising cooperating pressing members with means to carry out the opening and closing operation, a pressing member

thereof being provided with a spray chamber having openings leading to the work inserted in between the members, means for discharging steam into the spray chamber which ejects onto the work through the spray chamber openings, 80 an air heating reservoir, a connection established between the air heating reservoir and the spray chamber by which hot air is blown upon or through the work, and means connected with the spray chamber for producing a cold air draught 85 on the work.

14. A machine comprising in combination, co-operating pressing members, means for opening and closing the same, a member thereof provided with a plurality of chambers, means for supplying a heating medium to one chamber to heat the pressing member, means for passing air through another chamber for heating the air, a foraminous face plate being provided across one chamber permitting atmospheric communication, means for conveying the heated air to the foraminous faced chamber, and means for circulating cold air through the said foraminous faced chamber.

90 15. A machine comprising in combination; co- 100 operating members having opening and closing mechanism; a pressing member thereof made hollow with subdividing partitions setting said chamber off into a foraminous faced steam and air spray chamber, a steam heating chamber, and 105 an air heating chamber; control means for ejecting steam from the steam heating chamber into the foraminous chamber, and control means for ejecting air from the air heating chamber into the foraminous chamber.

110 16. A machine comprising in combination; co- operating members having opening and closing mechanism; a pressing member thereof made hollow with subdividing partitions setting said chamber off into a foraminous faced steam and 115 air spray chamber, a steam heating chamber, and an air heating chamber; control means for ejecting steam from the steam heating chamber into the foraminous chamber, control means for ejecting air from the air heating chamber into 120 the foraminous chamber, and cold air suction means for drawing air through the foraminous faced chamber.

17. A pressing machine comprising in combination cooperating pressing members, means for 125 opening and closing the press, a pair of forms upon which garments are carried and one of the forms being adapted to move into the press and hold the garments while being treated while the other form is outside the press being filled with 130 garments, and a support to carry each form and guide it in and out of the pressing machine independently one of the other.

18. A pressing machine comprising in combination cooperating pressing members, means for 135 opening and closing the press, a pair of independent and separately movable forms upon which garments are carried and one of the forms movable into the press while the other form remains stationary outside the press and being filled 140 with garments, an independent support to carry each form and guide it in and out of the pressing machine, a printing tape reel carried by the pressing machine and adapted to hold transfer tape across the garments in the press.

145 19. A pressing machine in combination, comprising pressing members, mechanism for opening and closing the press, a pair of frame units mounted on each end of the machine and including a plurality of garment forms which swing 150

- in and out of the press such that while one unit is being pressed the other is being filled with garments, and a printing device cooperating with the pressing machine for simultaneously printing the plurality of garments in the press. 80
20. A pressing machine comprising in combination, pressing members, operating means for opening and closing the press, an arm support standing outwardly from the machine, a two-motion pivot hub journaled on the arm and including means rotatable about a vertical and horizontal axis, and a garment carrying frame supported by the hub to swing in and out the pressing machine. 85
- 15 21. A pressing machine comprising in combination, pressing members, operating means for opening and closing the press, an arm support standing outwardly from the machine, a two-motion pivot hub journaled on the arm and including means rotatable about a vertical and horizontal axis, a garment carrying frame supported by the hub to swing in and out the pressing machine, and adjusting means related with the hub to bring the frame into alignment with the 90
- 20 hub to bring the frame into alignment with the 95
- 25 pressing members.
22. A pressing machine comprising in combination, pressing members, operating means for opening and closing the press, an arm support standing outwardly from the machine, a pivot hub journaled on the arm and including means rotatable on a vertical and horizontal axis, a garment carrying frame supported by the hub and arranged to swing in and out the pressing machine and swing at an angle thereto for loading and unloading a printing mechanism for printing the garments, and manually operated means for controlling the action of the printing mechanism. 100
- 30 23. A machine comprising in combination, jaws into which the work is inserted, means for operating the jaws, printing mechanism related with the jaws and supporting printing material, operating means forming part of the mechanism by which the printing material is advanced through the jaws, means related with the jaws to steam spray the work to be printed, means for heating the jaws, means for blowing hot air over the work, means for drawing cold air through the work, and garment carrying forms arranged to move in and out of the machine to press and print 105
- 40 garments.
- 45 24. A machine comprising in combination, operating jaws into which the work is inserted for treatment, a transfer printing tape reel, means for supporting the reel on one of the jaws, means for moving the reel into and out of alignment with the jaws for performing a printing operation every other time the jaws close, jaw operating means, and a garment carrying form movable into the jaws for pressing garments under one 110
- 50 jaw movement and for printing the garments under the next jaw movement. 115
- 55 25. A machine comprising in combination jaws, operating mechanism to open and close the jaws, brackets carried by one of the jaws, reels carried by the brackets, a handle conveniently located for manual operation and attached to the reels for moving them into and out of alignment with the jaws, a crank located conveniently to the operator for revolving the reels, and garment carrying forms movable in and out of the pressing machine. 120
- 60 26. A machine comprising in combination, cooperating pressing members, means for opening and closing the same, a member thereof provided with a plurality of chambers, means for supplying a heating medium to one chamber to heat the 125
- pressing member, means for passing air through another chamber for heating the air, a foraminous face plate being provided across one chamber permitting atmospheric communication, means for conveying the heated air to the foraminous faced chamber, means for circulating cold air through the said foraminous faced chamber, means for circulating steam through said foraminous faced chamber, garment forms movably carried by the machine and movable into and out of the machine to finish garments by treating them to steam, heat, and air, and means carried by the machine for printing the treated garments. 130
27. A pressing and printing garment finisher comprising in combination, a frame, a pair of swinging arms carried by the frame, garment forms carried by each arm, head and buck pressing members to press down on one set of forms while the other is being filled with garments, head closing means, and a garment printing device 135
- cooperating with the finisher. 140
28. A pressing and printing garment finisher comprising in combination, a frame, a pair of swinging arms carried by the frame, garment forms carried by each arm, head and buck pressing members to press down on one set of forms while the other is being filled with garments, head closing means, a printing device carried by the 145
- pressing members, and an operating means to swing the device in and out of the press. 150
29. A pressing and printing garment finisher comprising in combination, pressing members, garment forms swingable into and out of the pressing members, adjustment means to bring the forms into alignment with the pressing members, means for operating the pressing members, a printing device carried by the machine, and means for removing the printing device from the press during the pressing stroke and for returning the printing device into the press during the 155
- printing stroke. 160
30. A machine comprising in combination, pressing jaws mounted in a horizontal plane and made elongated in shape to receive garments for drying and pressing operations, a pair of shafts 165
- one end of each of which is pivoted on the machine at each end of the elongated press jaws and each of which is adapted to swing horizontally toward the said jaws and into parallel relation thereto, and a plurality of spaced garment holding forms carried by each shaft arm in the nature of a garment former unit to swing to and from the pressing jaws and project from the shaft into the press. 170
31. A machine comprising in combination, 175
- pressing jaws mounted in a horizontal plane and made elongated in shape to receive garments for drying and pressing operations, a pair of shaft arms having the ends thereof pivotally attached to the machine at each end of the elongated press jaws and each of which is adapted to horizontally swing toward and from the said jaws, a plurality of garment holding forms carried by each shaft arm and a pivot standard to support each shaft arm and forms in operative position. 180
32. A machine comprising in combination, 185
- pressing jaws mounted in a horizontal plane and made elongated in shape to receive garments for drying and pressing operations, a pair of shaft arms having the ends thereof attached to the machine at each end of the elongated press jaws and each of which is adapted to horizontally swing toward and from the said jaws, a plurality of garment holding forms carried by each shaft arm 190
- 195

- in the nature of a garment former unit to swing to and from the pressing jaws, a pivot standard to support each shaft arm and forms in operative position to swing in and out of the jaws, and a 5 double pivot hub carried by each standard by which each shaft arm is swung in a horizontal or vertical plane.
33. A machine comprising in combination, 10 pressing jaws mounted in a horizontal plane and made elongated in shape to receive garments for drying and pressing operations, a pair of shaft arms having the ends thereof attached to the machine at each end of the elongated press jaws and each of which is adapted to horizontally swing toward and from the said jaws, a plurality 15 of garment holding forms carried by each shaft arm in the nature of a garment former unit to swing to and from the pressing jaws, a pivot standard to support each shaft arm and forms in 20 operative position to swing in and out of the jaws, a double pivot hub carried by each standard by which each shaft arm is swung in a horizontal or vertical plane, and a vertical adjusting means by which the height of the arm is regulated on the 25 standard.
34. A machine comprising in combination, 30 pressing jaws mounted in a horizontal plane and made elongated in shape to receive garments for drying and pressing operations, a pair of shaft arms having the ends thereof attached to the machine at each end of the elongated press jaws and each of which is adapted to horizontally swing toward and from the said jaws, a plurality of garment holding forms carried by each shaft arm 35 in the nature of a garment former unit to swing to and from the pressing jaws, and a vertically adjustable pivot on which the said arms swing and by which the garment forms are adjusted into alignment with the pressing jaws.
35. A machine comprising in combination, 40 pressing jaws to receive garments for drying and pressing operations, a pair of shaft arms having the ends thereof attached to the machine at each end of the press jaws and each of which is adapted to horizontally swing toward and from the said jaws, a plurality of garment holding forms carried by each shaft arm in the nature of a garment former unit to swing to and from the pressing jaws, and a substantially U-shaped work 45 table under the horizontal jaws and under the outstanding garment forms to receive the work as it comes to and leaves the machine.
36. A machine comprising in combination, 50 pressing jaws to receive garments for drying and pressing operations, a pair of shaft arms having the ends thereof attached to the machine at each end of the press jaws and each of which is adapted to swing toward and from the said jaws, a plurality of garment holding forms carried by each 55 shaft arm in the nature of a garment former unit to swing to and from the pressing jaws, and a pair of spaced tables supported on the machine and standing outwardly therefrom in parallel relation and over which each arm and garment former unit stands when applying and removing garments upon and from the forms.
37. A machine comprising in combination, 60 pressing jaws mounted in a horizontal plane and made elongated in shape to receive garments for
- drying and pressing operations, a pair of shaft arms having the ends thereof attached to the machine at each end of the elongated press jaws and each of which is adapted to horizontally swing toward and from the said jaws, a plurality 65 of garment holding forms carried by each shaft arm in the nature of a garment former unit to swing to and from the pressing jaws, a pedal jaw opening and closing means arranged between the swinging garment former units, and a short motion toggle connection established between the pedal and a jaw by which the jaws are opened a short distance to admit the entree of former units.
38. A machine comprising in combination, 70 pressing jaws, means for opening and closing the jaws, a shaft extending along the edge of and parallel to the jaws and spaced therefrom so as not to interfere with the opening and closing operation, a plurality of garment forms fixed on the shaft and disposed between the jaws, and pivot means mounting one end of the shaft by which the shaft and forms swing on the pivot to and from the press.
39. A device for handling garments in the 75 pressing and finishing thereof comprising a shaft or rod, a plurality of garment forms fixed thereto, handles fastened to the shaft by which the device is handled by operators, and in combination with heated members into which the device may be inserted for drying or pressing the work.
40. A device for handling garments in the 80 pressing and finishing thereof comprising a shaft or rod, a plurality of garment forms fixed thereto, handles fastened to the shaft by which the device is handled by operators, in combination with heated members into which the device may be inserted for drying or pressing work, and printing means associated with the device and 85 members by which garments on the form are printed.
41. A machine comprising in combination, 90 a U-shaped work table including an opening within which an operator works, pressing jaws disposed above the U-shaped table, a pedal operating device disposed within the opening of the U-shaped table and adapted to open and close the jaws, and a garment form unit movably carried above the table and movable into and out 95 of the jaws.
42. A machine comprising in combination, 100 a U-shaped work table having an opening within which an operator works, pressing jaws disposed above the U-shaped table, a pedal operating device disposed within the opening of the U-shaped table and adapted to open and close the press, a garment form unit movably carried above each outstanding part of the table and movable into and out of the jaws, a printing mechanism 105 mounted above the table in proximity to the jaws, and manual means conveniently located to the operator inside the table opening and connected with the printing mechanism whereby the machine jaws first close upon the work and subsequently perform the printing operation upon the work.

EDWARD J. SCHREMP.
